UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

ROOF STRUCTURE FOR METAL VESTIBULE-CAR DIAPHRAGMS.

1,256,058.

Specification of Letters Patent.

Patented Feb. 12, 1918.

Original application filed April 24, 1916, Serial No. 93,135. Divided and this application filed February 1, 1917. Serial No. 145,913.

To all whom it may concern:

Be it known that I, HARRY H. SCHROYER, a citizen of the United States, and a resident of the city of Chicago, in the county 5 of Cook and State of Illinois, have invented certain new and useful Improvements in Roof Structures for Metal Vestibule-Car Diaphragms; and I do hereby declare that the following is a full, clear, and exact description of the same, reference being had to the accompanying drawings, and to the numerals of reference marked thereon, which form a part of this specification.

This application consists of a division of 15 my co-pending application for "metal vestibule car diaphragms", filed April 24, 1916, Serial No. 93,135.

This invention relates to an improved type of metal vestibule car diaphragm where- 20 in a construction is utilized to permit expanding movement of the diaphragm with reference to the car on which it is attached, and with means forming a part of the construction for providing a weather 25 proof seal at the roof structure of the dia- phragm and in movable connection therewith to the car.

It is an object therefore of this invention to provide in combination with a metal car 30 diaphragm construction utilizing parts ad- justably associated to permit expansion and contraction of the diaphragm with respect to the car, of a sealing means to seal the connection of the diaphragm along the 35 roof portion thereof at the point of connection with the car to insure weather proof passage on the interior of the diaphragm.

It is also an object of this invention to construct in combination with a metal car 40 diaphragm comprising a stationary and movable section, means associated with the car and co-acting with the movable section to afford a seal at the point of connection thereof with the stationary section to insure 45 a weather proof passage through the diaphragm on the interior thereof.

It is furthermore an important object of this invention to provide a sealing means for a telescoping car diaphragm to insure 50 a weather proof connection between the parts of the diaphragm in all positions of ad-

justment and variations in movement thereof.

It is finally an object of this invention to construct an adjustable car diaphragm pro- 55 vided with simple and efficient sealing means.

The invention (in a preferred form) is illustrated in the drawings and hereinafter more fully described.

In the drawings:

Figure 1 is a fragmentary side view with parts broken away and shown in section of two car diaphragms connected one to another and mounted on the ends of cars cou- 65 pled together.

Fig. 2 is a fragmentary detail section taken on line 2-2 of Fig. 1, with parts omitted and parts shown in elevation on line 2-2 of Fig. 1.

Fig. 3 is a fragmentary detail section on line 3-3 of Fig. 1.

Fig. 4 is a fragmentary detail section on line 4-4 of Fig. 1, with parts shown in elevation.

Fig. 5 is a fragmentary detail section taken on line 5-5 of Fig. 1, with parts omitted and parts shown in elevation.

Fig. 6 is a fragmentary top plan view of the diaphragm construction, with parts 80 broken away and parts shown in section.

Fig. 7 is a detail section taken on line 7-7 of Fig. 5.

As shown in the drawings:

The reference numeral 1, indicates as a 85 whole the end of a car, and movably mounted beneath the platform thereof (not shown) is a channel 2, forming the front member of a platform buffing mechanism of any usual and well known construction 90 secured and supported on which is a vesti- bule diaphragm face plate 3. As clearly shown in Fig. 1 an auxiliary buffing mechanism for the upper end of the face plate 3, is also provided, comprising a hori- 95 zontally rearwardly directed rod 4, securely attached upon the rear surface of the face plate 3, extending rearwardly and slidably through certain frame members of the car body, and having a compression spring 5, 100 coiled thereabout, adapted to resist inward sliding movement of said rod with similar

movements of the face plate and vestibule diaphragm. Forming a part of the car construction at the upper end thereof is a gabled or acute angled horizontally extending stationary roof plate 6, the rear margin of which is turned upwardly, and riveted or brazed to a vertical frame plate 7, forming a part of the car body, and the forward margin of which is secured to and beneath a built-up end plate construction 8, disposed beneath and supporting the end portion of the curved roof of the car.

Secured in any suitable manner to the front surface of the vertical frame plate 7, and projecting outwardly therefrom in parallel relation to the gabled top or roof plate 6, and of less width than the plate 6, is another gabled plate 9, which is flanged downwardly at its side and forward margins and attached to a horizontal ceiling plate 10, of the vestibule of the car, affording a compartment through which the associated rod 4, and spring 5, extend.

Secured in upright position on each side of the end of the car body are large channels, having an inner wall 11, and an outer wall 12, with the forward or outer margins of said respective walls flanged outwardly as clearly shown in Fig. 3. Provided upon each side of the car body are upright I-beams 13, and the respective channel members 11-12, of the vestibule diaphragm are secured thereto by angle irons 14 and 15, respectively, riveted to the flanges of said I-beams and to the side walls 12, of the channel members.

The elements of the movable section of the diaphragm are connected upon the face plate 3, and for this purpose a rearwardly tapered gabled roof plate member 16, is flanged at its forward margin and riveted to the rear surface of said face plate, as clearly shown in Figs. 1 and 2, and extends rearwardly beneath the gabled top plate 6, and over the gabled top wall of the compartment or abutment member 9. Near its side margins, guide or abutment members 17, of trapezoidal section, as shown in Fig. 2, are provided, each consisting of a plate bent longitudinally into trapezoidal form and riveted or brazed beneath the surface of the roof plate 16, near the side margins thereof, and spaced therefrom to afford a recess therebetween. Slidably inserted in the recess above the trapezoidal abutments are wing plates 18, which, at their forward ends are connected by means of a pivot 19, to the roof plate 16, and each provided with a downwardly extending flange, the rear end of which fits slidably within the channels of the stationary diaphragm section, as clearly shown in Figs. 4 and 5.

As shown in Fig. 5, the top horizontal margin of the outer wall 12, of the channel

11-12, merely extends upwardly to afford an abutment against which the downwardly turned flange of the wing plate 18, may contact, while the inner wall 11, has its upper margin flanged inwardly in horizontal position and rigidly secured in any suitable manner by riveting or brazing beneath the ceiling plate 10, of the vestibule of the car.

Also secured adjustably to the face plate 3, on the rear surface thereof, are the side walls of the movable section of the diaphragm each comprising resilient angled divergent walls 21 and 22, respectively, integrally connected in a rounded bead portion 23, and with the rear margins of said respective wall members provided with strips of sealing material 24, which, owing to the resiliency of the wall members 21 and 22, are thrust into sealing contact with the interior surfaces of the channel walls 11 and 12. The upper margins of the wall members 22, are turned horizontally inwardly and provided with sealing strips 20, which bear upwardly beneath the flat surfaces of the trapezoidal abutment members 17, of the roof plate 16.

For the purpose of attachment of said resilient side walls 21-22, to the face plate 3, a pair of plates 25 and 26, are bolted on the rear surface of the face plate with the margins thereof curved, as clearly shown in Fig. 3, to afford a cylindrical recess within which the rounded or beaded portion 23, of said divergent wall members 21 and 22, fits and is capable of movement therein.

A sealing mechanism is provided for the roof plate 16, at the point at which the same slides inwardly within the car end beneath the gable top plate 6, and for this purpose, as clearly shown in Figs. 1 and 7, a pair of angled plates 30 and 31, respectively, are secured in inclined position on the built-up end plate member 8, of the car projecting outwardly therefrom with their lower margins spaced from one another and having mounted therein a sealing strip 32, normally impelled downwardly into contact with the top surface of the gabled roof plate 15, by springs 33.

The operation is as follows:—

Due to the flexible connection on the face plate 3, to the side wall members 21-22, of the movable diaphragm section, a flexing or weaving movement between the same is readily permitted and furthermore, owing to the fact that no rigid connection exists between the gable roof plate 16, of the movable diaphragm section and the side walls 21-22, thereof, adjustments with respect thereto due to variations in movement of the diaphragm with respect to the car, are also readily permitted. The telescoping movement of the movable diaphragm section composed of the side walls 21-22, and roof plate member 16, are readily permitted, owing to the fact that the resilient side

wall members 21-22, telescope within the fixed upright channel members 11-12, of the stationary diaphragm section, and the roof plate member 6, sliding beneath the 5 sealing strip 32, provided at the upper end of the car.

A certain angular movement of the face plate 3, with respect to the elements of the movable diaphragm section is permitted, and

- 10 when such movement takes place, of course, the face plate has a hinged action on the cylindrical or beaded portions 23, of the side walls 21-22, but the gabled roof member 16, moves as a unit therewith, and owing
- 15 to the fact that the side margins thereof are tapered inwardly, as shown clearly in Fig. 6, the same is capable of swinging laterally with respect to the elements of the stationary diaphragm section. A seal between the
- 20 gabled roof plate member 16, of the movable diaphragm section and its side walls 21-22, is effected by the pivotally mounted wing plates 18, which engage in the recess provided therefor beneath the side margins
- 25 of the roof plate 16, and are turned downwardly to overlap the upper edge of the side wall members 22. As a consequence, when the swinging movements of the roof plate member 16, take place as the vestibule
- 30 face plate 3, is caused to assume an angled position, the wing plates maintain substantially the same relation with the side walls 21-22, and the roof plate 16, slides with reference thereto, the seal, however, being
- 35 always maintained, and when the associated roof plate 16 and wing plates 18, move inwardly with respect to the stationary diaphragm section, said wing plates 18, engage within the channel members 11-12,
- 40 contacting the inner surface of the walls 12.

I am aware that various details of construction may be varied through a wide range without departing from the principles of this invention, and I therefore do not pur-
45 pose limiting the patent granted otherwise than necessitated by the prior art.

I claim as my invention:

- 1. The combination with a telescoping metal car diaphragm of spring impelled means mounted on the car and co-acting with the diaphragm to afford a seal between the same and the car.
- 2. The combination with a telescoping metal car diaphragm of spring impelled means mounted on the end of the car and
- 55

co-acting with the roof portion of said dia- phragm to afford a seal between the dia- phragm and the car.

3. The combination with a telescoping car diaphragm of spring impelled means inde- 60 pendent of the diaphragm co-acting with a movable portion thereof to afford a seal be- tween the diaphragm and the car to which it is attached.

4. The combination with an apex type 65 of telescoping metal car diaphragm of re- sili-ent means mounted on the car and con- tacting the apex roof member of the dia- phragm to afford a seal between the same and the car.

5. The combination with an apex type of 70 diaphragm of resilient means mounted on the car co-acting therewith to afford a seal between the diaphragm and the car.

6. The combination with a car diaphragm 75 one part of which is movable, a downwardly opening channel member secured to the car, a sealing strip movable in the channel and bearing against the movable roof member to afford a seal, and springs in the channel 80 member yieldingly holding the sealing strip against the movable roof member.

7. In a metallic diaphragm roof construc- 85 tion, the combination with metallic tele- scoping roof sections, and a sealing mech- anism attached to the car above the roof sec- tions and bearing on the top of one of the telescoping sections.

8. A sealing device for a metal roof dia- phragm comprising in combination with the 90 telescoping roof sections, a channel member secured rigidly on the car and a spring pressed sealing means in said channel.

9. The combination with a telescoping metal car diaphragm, of a longitudinally 95 slid- able roof member capable of lateral swinging movement, and sealing means yieldably mounted upon the car to bear upon the exterior surface of said member, and permit longitudinal sliding and lateral 100 swinging movements thereof to take place, affording a seal therealong.

In testimony whereof I have hereunto sub- 105 scribed my name in the presence of two sub- scribing witnesses.

HARRY H. SCHROYER.
